UNITED STATES PATENT OFFICE

2,431,951

TERMINAL BUSHING

Leopold Mauerer, Chicago, Ill., assignor to Jefferson Electric Company, Bellwood, Ill., a corporation of Illinois

Application May 24, 1944, Serial No. 537,050

2 Claims. (Cl. 174—153)

1

This invention relates to an improved terminal bushing for casings for transformers and other electrical apparatus, and in particular to an improved construction which provides an air-tight seal between the casing, the conductor and the bushing proper.

The usual type of bushing for small transformers and the like comprises a body of insulating material disposed in or adjacent an aperture in the casing, and which serves to space a conductor passing through the bushing from the edges of the apertured casing. Various expedients are used to provide an air-tight construction between the insulating body and the metal casing. The screw threaded clamping means frequently used on large transformer bushings is not practicable for considerations of space in small radio transformers and the like. Other expedients involve the use of a shaped member of U or S-shaped cross-section which clamps both the insulating body and the edge of the transformer casing to provide an air-tight construction. This expedient, however, is not entirely satisfactory for the reason that the ring-shaped member is exposed and is subject to blows or other forces which might dent or otherwise deform it in a manner to break the seal.

This invention contemplates the use of a ring-shaped member which is associated with the insulating body in a non-exposed and protected manner, and which, being spun over the edge of the apertured casing, cannot be bent or deformed so as to break the seal by any exterior force, except as such force may be great enough to damage the insulating body as well.

It is an object of this invention to provide a terminal bushing which is secured to the casing of a transformer or the like by a skirt which is partially embedded in the insulating body of the bushing.

It is a further object of this invention to provide a transformer bushing having a body member of relatively shockproof plastic material in combination with a skirt in the form of a molded insert depending from the casing contacting surface of said body member, so that the bushing may be secured to the casing in an air-tight manner.

It is another object of this invention to provide in a terminal bushing which is adapted to

2

overlie an aperture in a transformer casing or the like, a barrier to the passage of air along the contacting flat surfaces, this barrier being in the form of a cylindrical member secured at either end to the body of the bushing and to the transformer casing, and which surrounds the conductor leading up to a terminal in the bushing.

It is a still further object to provide a terminal bushing for cooperation with an apertured transformer casing or the like which includes a terminal to which a conductor may be secured in air-tight relationship, and which bushing is otherwise secured in an air-tight relationship to the transformer casing.

Other objects, features and advantages will appear as this description proceeds.

With reference now to the drawings which form a part of this description and in which like reference numerals designate like parts:

Fig. 1 is a view of a small transformer embodying a preferred form of this invention;

Fig. 2 is an enlarged plan view of a terminal bushing shown in Fig. 1;

Fig. 3 is a sectional elevation of the transformer bushing shown in Fig. 2;

Fig. 4 is a phantom elevation of the bushing shown in Fig. 3;

Fig. 5 is a section of a modified form of this invention; and

Fig. 6 is a section of a further modification.

With reference now to Figs. 1 to 4, the reference numeral 10 designates generally a transformer which includes a cover 11, or other portion of the transformer casing, and a plurality of terminal bushings 12.

Each terminal bushing comprises a body member 13, as shown in Fig. 3, which is preferably formed of a plastic having a relatively high impact test. It has been found that a phenolic molding material which is mineral filled and has high heat resistance and high impact strength is particularly well adapted for the terminal bushing herein shown and described.

45 The body member is molded with two inserts, a central tubular insert 14, and a cylindrical skirt 17. The lower surface of the body member may be recessed centrally of the skirt 17 and the lower end of the tubular insert 14 is flush with the recessed surface. The upper end thereof is

extended beyond the upper surface of the body member 13. The tubular insert is provided with an annular crimp or ridge 15 which is milled as indicated at 16 in Fig. 4, this configuration serving to anchor it in the plastic body member against both longitudinal and rotational displacement.

The insert which comprises the cylindrical skirt 17 is molded in the body member so that the lower end thereof extends beyond the bottom surface of the body member. The upper end of the insert comprises an expanded edge 18 which is provided with milling 19 so as to prevent longitudinal and rotational displacement.

In assembling the bushing, an L-shaped terminal 23, the lower end of which is apertured, is placed over the extended end of the tubular insert 14, and this extended end is spun over the terminal 23 as indicated by the reference numeral 25. The L-shaped terminal may be provided with burrs 24 which bite into the body member of the bushing to prevent rotation.

The bushing is now seated over the circular aperture formed in the cover 11. The edge of the aperture is designated by the reference numeral 27, and after the skirt 17 is fitted into the apertured casing the lower end thereof is spun over the edge 27 as indicated by the reference numeral 28. The joint between the skirt and the casing may be filled with a bead of solder 29. The solder provides an air-tight connection.

Then a conductor 29, the end of which has been bared of its insulation 21, is brought up through a circular aperture in the transformer cover 11, and is inserted into the central tubular insert 14, and the space between the two is filled with solder 22. This not only proves a good electrical connection but also insures an air-tight joint.

The cover 11 is then replaced on the transformer and a conductor to an external circuit may be soldered to the terminal 23. The latter is provided with an aperture 26 through which said external conductor to an exterior circuit may be threaded prior to soldering.

It will be observed from a consideration of Fig. 3 that any tendency of air to creep between the contacting surfaces of the bushing and of the casing is prevented by the skirt 17 which provides an impenetrable barrier. The fact that this skirt is a molded insert prevents any leakage of air upwardly and around its surface due to the intimate nature of the contacting surfaces. The bead of solder 29 prevents any leakage of air downwardly around the skirt. Similarly, the solder 22 prevents any leakage of air through the central tubular insert.

If preferred, a gasket may be disposed between the plastic body member 13 and the cover 11, instead of providing the bead of solder 29, such as shown in Fig. 6, or both may be used. However, a solder seal is preferred from the viewpoint of ease of manufacture.

Inasmuch as the cylindrical skirt 17 is wholly enclosed, it cannot be bent or otherwise damaged by a blow. Furthermore, the use of a high impact plastic will serve to protect the skirt 17 from the effect of blows on the body portion 13.

A modified form of this invention is shown in Fig. 5, this modification being substantially identical to that shown in Figs. 2 to 4, with the exception that the central portion 30 of the body member 13' projects downwardly. The Fig. 5 bushing comprises a body member 13' having a skirt 17' molded into the lower surface thereof.

The central tubular insert 14' is longer than the insert 14 of Fig. 3; the insert 14' extends all the way through the body member 13' and the projecting central portion 30.

5 A further modification, adapted for somewhat larger installations, is shown in Fig. 6 and comprises a molded plastic body member 31 having a central insert 32 provided with exterior and internal terminals 33 and 34 respectively. An enlarged intermediate portion 35 is provided with a coarse knurl 36 so that the insert 32 may be securely embedded in the body portion 31. The central insert 32 is considerably larger than the body portion, and the downwardly extended portion 37 of the insert is embedded in a sleeve 38 which is integral with and extends downwardly from the body portion 31.

10 In assembling the bushing, an L-shaped skirt 39, in the form of a cylindrical skirt, projects from the lower surface of the body portion 31. This is substantially the same as the skirt 17 of Figs. 3 and 4, and is embedded in the plastic body member in the same way as described above.

15 The bushing is assembled to the cover 11' in much the same way as the bushing of Figs. 2 to 4, except that Fig. 6 shows, by way of variation, the use of a gasket 40 between the bushing and the cover to provide an air-tight seal, instead of a bead of solder around the spun over edge of the skirt.

20 The internal terminal 34 then is provided with a shallow bore and cut away edges so as to form a tubular extension 41 which is spun over a terminal clip 42 to which an internal conductor can be soldered.

25 An external conductor can be soldered to the external terminal 33.

30 Although only preferred embodiments of this invention have been shown and described herein, it will be understood that various modifications and changes therein may be made without departing from the spirit of this invention. The drawings and the foregoing description are deemed to be illustrative only and this invention is to be limited only by the appended claims.

35 I claim:

1. A terminal bushing comprising a plastic body member having a central tubular insert projecting from the upper surface thereof and extending all the way through said body member and a tubular insert concentrically disposed with respect to said first mentioned insert, and projecting from the bottom surface of said body member, said central tubular insert being adapted to receive a conductor, and said second mentioned insert being deformable for engagement with the edge of an apertured transformer casing or the like, and an apertured terminal member fitting over the projecting portion of said first mentioned tubular insert, and provided with burrs which bite into said upper surface, said first mentioned tubular insert being spun over into engagement with said terminal member.

2. A terminal bushing comprising a plastic body member having a central tubular insert projecting from the upper surface thereof and extending all the way through said body member and a tubular insert concentrically disposed with respect to said first mentioned insert, and projecting from the bottom surface of said body member, said central tubular insert being adapted to receive a conductor, and said second mentioned insert being deformable for engagement with the edge of an apertured transformer casing or the like, and an apertured terminal member fitting over the pro-

jecting portion of said first mentioned tubular insert, said first mentioned tubular insert being spun over into engagement with said terminal member.
